UNITED STATES PATENT OFFICE.

BENJAMIN B. ENGLANDER, OF BROOKLYN, NEW YORK, ASSIGNOR TO ENGLANDER SPRING BED COMPANY, OF BROOKLYN, NEW YORK, A CORPORATION OF NEW YORK.

HAMMOCK.

Application filed October 28, 1921. Serial No. 511,146.

To all whom it may concern:

Be it known that I, BENJAMIN B. ENGLANDER, a citizen of the United States, residing at Brooklyn, in the county of Kings and 5 State of New York, have invented certain new and useful Improvements in Hammocks, of which the following is a specification.

This invention relates to hammocks, more 10 particularly to that kind generally known as couch hammocks, which usually comprise a spring formed seat, a back and a pair of ends, by means of the latter of which the seat is suspended. Heretofore it has been 15 the usual practice to form these ends in the nature of wind shields of a suitable fabric or flexible material, as duck, or canvas, and of the same height as the back, but recently hammocks have been placed upon the market in which these fabric end wind shields 20 have been lowered somewhat so that the upper edges will form arm rests whereby the structure is more comfortable for the user. However, as this form of ends does not make 25 the hammock any more attractive or pleasing in appearance than the previously formed higher ends, the object of the present improvement is to provide hammock ends by means of which the seat of the hammock 30 may be suspended, so located with the height relatively to the height of the back, that the upper edges will form arm rests, but also so constructed that they will give an added attraction and pleasing appearance 35 to the hammock whereby a more attractive article of furniture than has heretofore been possible is provided.

With fabric formed ends, even when so located as to form arm rests, it is not possible 40 to add very much in the way of attractiveness to the hammock, since the only ornamentation they can have is stripes or something of that sort, since it is necessary that these fabric ends have sufficient 45 strength to support the hammock, as all the weight thereof comes upon these ends, and furthermore the use of fabric ends makes it difficult to form a sufficiently safe connection between them and a metallic formed 50 seat or framework.

Therefore the object of the present improvement is to provide a couch hammock with an entirely different form of end whereby a safer connection between the ends 55 and the seat is not only obtained, but a more

pleasing and attractive appearance given to the hammock as well as obtaining the arm rest feature, and for that purpose the ends in the present instance are formed of some rigid or solid formed material, such as 60 wood or sheet metal, which may be either decorated or may be covered with cretonne or other decorative material, thus giving to the hammock a rigid appearance as well as providing a safer structure and a more 65 pleasing effect.

In the drawings accompanying and forming a part of this specification, Fig. 1 is a front view of this improved hammock; Fig. 2 is likewise a front view thereof with 70 the seat cushions removed and the back detached; Fig. 3 is a cross sectional view taken on line 3—3 Fig. 2; and Fig. 4 is a detail sectional view of one of the means for detachably connecting the back to the seat. 75

Similar characters of reference indicate corresponding parts in the several figures of the drawings.

In the preferred form thereof, herein shown, the hammock comprises a seat portion or framework 2 usually of metal consisting of a pair of lengthwise extending bars 3 and a pair of angle formed cross bars 4, between which the metallic fabric is stretched, and for this purpose in some 80 forms thereof coiled springs 5 are used. These cross angle bars are provided with upright lugs or ears 6 having openings therein for the purpose hereinafter described. The back 7, which may be of any 85 suitable form, is herein shown as comprising a spring formed portion 8 having secured thereto a cushion or pad 9. This back is provided with a plurality of depending hooked portions 10 adapted to enter slots 11 located in the rear or extending bar of the seat frame whereby the back may be 90 adjusted or by bending it over on the seat, readily detached. The ends of the hammock are constructed of some suitable rigid 100 or solid material, such for instance, as wood, although metal or any other generally similar material could be used if desired. These ends are of such height relatively to the height of the back that the upper edges 105 thereof are in position to form arm rests 12 and therefore they are materially below the upper edge of the back. These ends are supported by some suitable or flexible means as chains 13, preferably having in 110

their length coiled springs 14, by means of which greater resiliency is given to the hammock, and the back is adjustably supported relatively to the seat by means of suitable connecting chains 15. The lower ends of the supporting chains are attachable to hooks 16 rigidly secured adjacent to the upper edge of each end, but so located that they do not interfere with the use of the upper edge of 10 the ends as arm rests.

These rigid ends are also provided with hooks 17 spaced above the lower edges of the ends, which are adapted to enter into the openings of the lugs of the seat and by 15 means of which the ends may be detachably connected with the seat. It will be observed that the ends are of sufficient length to extend to the under side of the seat, thereby somewhat protecting it as well as hiding it from view, especially when a flap 18 is 20 used along the front of the same, which hangs to the lower edges of the ends. By forming the ends of a suitable rigid material, such as wood, the necessity of using 25 a supplemental framework, such as described in my co-pending application for attaching the ends to the seat is avoided, since the form of ends shown enables the several hooks to be rigidly secured thereto 30 without the use of this intermediate framework.

From the foregoing it will be observed that not only is the back but the ends are 35 detachable from the seat, so that the whole structure can be readily knocked down either for shipping purposes or for storage purposes, and that the same can be readily folded into a compact structure so as to be stored away in a small space, and 40 that the several parts can be readily detached to avoid the necessity of lifting a heavy structure in the event that it is desired to protect the same against inclement weather.

The construction of the connection between the ends of the seat in the form shown it will be observed also permits the ends to be folded over upon the seat, as well as to permit the seat to be detached 45 from the ends, thus making it possible to not only knock down the whole structure, but whenever this is not desired to fold the ends over upon the seat in the same manner in which the back may be folded.

Furthermore it will be noted that the rigid 50 arm rest ends are not only freely detachable from the seat, but are located with relation to the seat so that relative swinging movement of the ends and seat is prevented, hence the upper arm rest portions are at all times located in substantially fixed or constant relation to the seat, as will be understood from Fig. 1. Where heretofore the arm rests were 60 flexibly connected to the seat, there was a tendency of the arm rests and ends to move 65

relatively endwise, which was objectionable to the user. In the present instance however, the arm rests are rigid extensions above the seat, and are substantially in fixed position with relation to the seat. Also, as in 70 this instance, they impart rigidity to the suspending means a substantial distance above the seat, and since the flexible suspension of the hammock terminates at the arm rests the tendency of the hammock to swing or 75 vibrate endwise is to a very considerable extent eliminated.

It will be understood that the various details may be more or less changed without departing from the spirit or scope of the 80 present improvement.

In the present form shown, the ends of the hammock are covered by cretonne or other suitable figured material as 20, which may be readily done by making such decorative 85 material in the form of slip covers, if preferred. By reason of the present improvement, the seat is suspended by the chains through rigid or solid end members, whereby a safer and more lasting connection is 90 possible with the seat.

I claim as my invention:

1. A couch bed formed hammock comprising a seat frame adapted to support a cushioned seat, substantially solid ends detachably hook-connected to the ends of the seat frame above the plane of said frame whereby the ends overlap the ends of the seat frame and of a height to have an upper portion in position to form arm rests, and suspension means connected to said ends for supporting the hammock. 95

2. A couch bed formed hammock comprising a spring formed seat frame adapted to support a cushioned seat, a cushioned back connected to said seat frame, substantially solid ends connected to the ends of the seat frame above the plane of said frame whereby the ends overlap the ends of the seat frame and of less height than the back and having an upper portion in position to form arm rests, and suspension means including coiled springs connected to said ends for supporting the hammock. 100

3. A couch bed formed hammock comprising a spring formed seat frame adapted to support a cushioned seat, a back connected to said seat, substantially solid ends connected to the ends of the seat frame at the inside of and at a point above the lower edges of said ends, said ends having a height less than that of the back and having an upper portion thereof in position to form arm rests, and suspension means connected to said ends for supporting the hammock. 115

4. In a couch hammock, the combination of a seat and a pair of rigid closed ends acting as rigid means extending above the seat for supporting the same, the top edges of the said ends being located in position to form 120

arms rests, said ends and seat having one openings and the other hooks for detachably connecting the ends and seat together, and a back, said back and seat having one 5 openings and the other hooks for detachably and adjustably connecting the seat and back.

5. In a couch hammock, the combination of a seat and a pair of rigid closed ends acting as rigid means extending above the seat 10 for supporting the same, the top edges of the said ends being located in position to form arm rests, hooks carried by said ends and releasably connected to the seat, a back, and freely releasable cooperating means carried 15 by the back and seat for permitting adjustment and detachment of the back.

6. A couch bed formed hammock comprising a spring formed seat frame adapted to support a cushioned seat, a back connected 20 to said seat, substantially solid ends connected to the ends of the seat frame at the

inside of and at a point above the lower edges of said ends, said ends having a height less than that of the back and having an upper portion thereof in position to form arm 25 rests, and suspension means including coiled springs connected to said ends for supporting the hammock.

7. A couch bed formed hammock comprising a spring formed seat frame adapted to 30 support a cushioned seat, a back connected to said seat frame, substantially solid ends hook-connected to the ends of the seat frame at the inside of said ends and above the lower edges thereof and of a height less than that 35 of the back and having an upper portion in position to form arm rests, and suspension means connected adjacent to the upper edges of said ends for supporting the hammock.

Signed at Brooklyn, New York this 26th 40 day of October, 1921.

BENJAMIN B. ENGLANDER.
